UNITED STATES PATENT OFFICE.

STANLEY W. HAYES, OF RICHMOND, INDIANA, ASSIGNOR TO HAYES TRACK APPLIANCE COMPANY, OF RICHMOND, INDIANA, A CORPORATION OF INDIANA.

PORTABLE DERAIL.

Application filed July 12, 1927, Serial No. 205,075. Renewed July 18, 1928.

This invention is an improvement on the portable derail of my Patent, No. 988,189, March 28, 1911, differing therefrom in various respects hereinafter pointed out and being 5 more compact, lighter and more readily applicable to the rail yet very stable and resistant to displacement under wheel impact. This derail like that of the said patent may be applied to rails of various weights, shapes 10 and sizes within a wide range.

Referring to the drawings:

Fig. 1 is an end elevation showing the derail applied to a rail of large size, the rail being shown in section.

15 Fig. 2 is an end elevation partly in section of the derail applied to a rail of small cross section.

Fig. 3 is a plan of the derail on the rail.

Fig. 4 is a view corresponding to Fig. 3, 20 certain parts being shown in section on the line IV—IV, Fig. 2.

Fig. 5 is a transverse vertical section through the clamping jaw between its ends, and

25 Fig. 6 is a horizontal section on the line VI—VI, Fig. 5.

The derail of this application differs from that of my said patent in having but one complementary member in place of two sets of 30 clamping jaws. This simplifies and lightens the derail and makes its application to the rail easier, but it necessitated the solution of problems incident to the change. In the patented derail the clamping means was subject 35 to little or no twisting strain. With but one clamping means, however, the twisting strain is severe and, where as in the illustrated derail a clamp screw is used, would bend or break the clamp-screw or cause the nut to 40 jam were not provision made to obviate such a result. The invention deals successfully with this difficulty, and also with the proper location of the clamping means with respect to the derailing member and with reference 45 to the road-bed abutment, which also must be rightly placed.

The derail block member 1 is cast or otherwise formed with a diagonal rib or groove 1^a 50 on its upper side constituting the "trough" of the derail and adapted to lift the flanges of passing wheels and guide them over the side of the rail in the usual way. This member is provided with a bearing surface, or bearing surfaces, 2 adapted to seat on the

tread of the rail and with a shoulder 3 which 55 seats on the side of the rail head. The sole complementary clamp member of the device is the jaw 4. This is of comparatively slender formation being tapered so as to be capable of being readily thrust between the base of the 60 rail and the sub-adjacent ballast or soil without special excavation of the latter, and terminates in a hook adapted to embrace or grasp the edge of the base flange of the rail at the other side of the rail. This jaw might have a 65 rail base bearing parallel to the rail, as in my patented derail, but it is far better to provide it with a rail-clamping contact portion 5 of suitable configuration in horizontal section, as convex, to give a rocking bearing on the 70 rail. Making the portion 5 concave in vertical section, as illustrated enables the hook to accommodate itself more readily to the base flanges of rails of different sizes. The operating means for this complementary clamp 75 member is constituted, in the illustrated derail, by the clamp-screw 6 mounted in and passing freely through the other clamp member, i. e. the derailing block member and having 80 bearings preferably constituted, as in my said patent, by bearing surfaces 7—8 formed respectively in a counter-sink and on the head of the clamp-screw so as to permit limited relative movement vertically in adjusting the 85 derail to rails of different heights. To avoid interference with movement of the clamp screw laterally, i. e. endwise of the rail, under car wheel impact, the hole through which the clamp screw passes is made substantially 90 larger than the clamp screw and is further enlarged at its inner side as indicated. This permits relative turning movement between the derail block and the clamp screw of sufficient extent to protect the means connecting 95 the complementary clamping members and to increase the clamping action materially. The particular arrangement illustrated constitutes a ball and socket joint. The clamp-screw may be provided with suitable means, as a removable collar, for preventing impairment of the thread by scraping back and forth through the hole. The end of the jaw 4 remote from its rail base engaging hook portion is free to swing about the bearing of its rail engaging end on the rail base, since 100 it is located at a considerable distance from any obstructive parts of the derail block member which otherwise would have blocked rela-

tive swinging movement of the derail member and clamp jaw under car wheel impact. Furthermore, the jaw 4 is provided with a bore 9, aligned with the hook of the jaw and adapted to receive the clamp-screw, and widened at each side laterally, i.e. endwise of the rail—in the construction illustrated in the plane of the axis of the bore and the rail-clamping bearing of the jaw, as indicated at 10. See Fig. 4 and also Figs. 5 and 6. This leaves room for relative turning movement of the connections in said plane endwise of the rail under car wheel impact. A progressively continuous widening from the inner end 15 of the bore to the outer end of the clamp as shown in Fig. 4 is preferable but not necessary. The screw clamp nut 11, which may be prevented by a cotter pin from being inadvertently run off the clamp-screw, is received 20 in a recess 12, adjacent the bore 9 and of such size and shape as to prevent rotation of the nut, and having an end wall or lip 13 to limit its endwise movement. This recess in which the nut is loosely held is wide enough to extend well beyond the nut at each side in said 25 plane and its bottom adjacent the laterally elongated bore has a surface 14, shown as substantially spherical about a center in the axis of the bore between the recess and the hook of the jaw. The rounded surface 15 of the head of the nut bears on the surface 14 with capability of limited movement, so that the turning movement of the connections lengthwise of the rail already referred to can 30 occur, thus relieving the clamp-screw from twisting strain incident to movement of the derail endwise of the rail under wheel impact. It will be understood that the parts are so dimensioned as to make provision for such 35 relative movement of the connections to the extent required. As shown most clearly in Figs. 4, 5 and 6, this recess or housing 12 is cut away except at and adjacent its front side so as to leave room for the insertion of the 40 nut while controlling its movement after insertion in the manner stated:

In the derail, as thus described and illustrated, a further supporting means is necessary and is provided in the roadbed abutment or leveling screw 16. This is threaded through the derailing block member with its axis vertical and is placed far enough out from the rail to be in line with the toe 1^b of the derail and so that the point 1^c of initial contact of the wheel flange is substantially in the said line or in advance thereof in the direction of car movement. This overcomes any tendency of the derail to tip over or swivel on the rail, the arrangement described constituting the derail a beam and not a lever. The abutment screw is located adjacent the central transverse plane of the derail between it and the heel of the derail, thus reducing the tendency of the derail to turn in its own plane (i. e. 45 horizontally). The clamp-screw is located

adjacent said transverse plane between it and the toe of the derail and as close as practicable to the abutment screw, which divides the downward component of the clamping action with the derail block, and thus sustains it 50 almost directly and substantially without leverage, being as nearly as possible under the clamp-screw bearing, the point at which the downward force is applied. In practice the axes of the screws which were 1^{1/4}" U. S. S. 55 have been located 2^{5/8}" apart with successful results. This is not to be understood however as a limitation to the distance given but as an illustrative example. The abutment screw 16 and the clamp-screw 6 are provided respectively with slotted handles 17, 18 for operating purposes and for locking, as with the padlock 19.

In operation the jaw 4 having first been 60 screwed down, its hook end is forced under the base of the rail adjacent a tie and engaged with the far side of the rail base. The levelling screw which, by virtue of the relative location of the levelling screw and the clamp-screw just described, abuts on the tie near its front edge, is then screwed to locate the derailing member at the desired height, the clamp-screw is screwed up to clamp the derail on the rail and the handles 17, 18 are 65 locked together.

The clamping-jaw being just in front of the tie is so placed that movement of the derail endwise of the rail under impact of the wheel carries the adjacent end of the jaw into contact with the side of the tie, which thus constitutes a stop for the jaw and derail. Owing to the relation between the clamp-screw and derailing member and between the clamp-screw nut and the clamping jaw, further movement of the derail results in 70 limited relative movement of the clamp-screw and clamping jaw endwise of the rail, the axes of the bore 9 and of the clamp-screw moving relatively out of line as shown in Fig. 4. This saves clamp-screw breakage and materially increases the clamping action. In the 75 derail of my said patent no appreciable or significant turning of the clamp jaw or connections endwise of the rail under car wheel impact can occur. In my present derail, as illustrated, the plural turning movement just described will ordinarily take place, but where the twisting effect under car wheel impact is fully taken care of by relative movement between the power means or connections and the derail block member, the power means or connections and the clamp jaw swing as a unit with reference to the 80 derail block member. Where, on the other hand, the twisting effect is taken care of partly or 85 solely by flexibility of the connections, as by relative turning of the clamp-screw bolt and clamp jaw, the clamp jaw and connections form a broken line.

Structure permitting such swinging or 90

turning movement endwise of the rail under car wheel impact is within the invention, whether the movement be a single or a plural turning, and regardless of which part, or 5 parts, turn to produce such movement, or what the particular nature or location of the power means employed may be. It will be understood further that particularity in describing the structure illustrated is for 10 clarity and convenience and is not to be taken as limiting the claims beyond the substance of the invention as respectively set forth therein.

Sliding of the derail endwise of the rail, 15 turning of the derail in the plane of the rail, and overturning of the derail about the rail are all guarded against by the construction of this derail, and stability on the rail thus assured in a compact and readily portable 20 derail.

Claims:

1. A portable derail having a derail block member adapted to engage one side of the rail, and a rail base flange clamp-jaw hook 25 having power means and mounted in the derail block member with freedom to assume an oblique position with reference to said power means under the car wheel impact.

2. A portable derail having a derail block 30 member, clamp means therefor comprising a rail base hook, and means flexible at more than one place under car wheel impact for connecting said hook to said block.

3. A portable derail having a derail block 35 member adapted to engage one side of the rail, clamp means therefor comprising a rail base hook adapted to engage the other side of the rail and to abut against the side of a tie, and means including two pivotal connections for connecting said hook to said 40 block with capability of relative turning of said hook and last named means under car wheel impact.

4. A portable derail having a derail block 45 member, clamp means therefor comprising a rail base hook having a rocker bearing on the rail base and adapted to abut against the side of a tie, and means including two pivotal connections for connecting said hook to said 50 block, both said connections being adapted for angular movement under car wheel impact.

5. A portable derail having a derail block 55 member, clamp means therefor comprising a rail base hook adapted to abut against the side of a tie, and means including two pivotal connections for connecting said hook to said block, one of which is a ball and socket bearing, said hook and said means for connecting it to the block having freedom to assume an oblique position with reference to each other under car wheel impact.

6. A portable derail having a clamp member 60 consisting of a derail block member adapted for engagement with the tread and

with one side of the rail head, a rail-base clamping member adapted for engaging the other side of the rail, and power means having bearings in the derail block member and operatively connected to said other clamping 70 member with capability of relative turning movement with respect thereto endwise of the rail under car wheel impact.

7. A portable derail comprising a clamp 75 member formed as a derail block member, and a tapered hook member adapted for insertion under the rail and for engagement therewith, in combination with a clamp-screw uniting said members with capability of relative turning movement of said clamp-screw and hook member endwise of the rail under car wheel impact.

8. A portable derail comprising a derailing member adapted to seat on the rail head 80 and an auxiliary clamping jaw for clamping the rail between them, said jaw having a rocking bearing on the rail, and operating means for effecting said clamping action mounted in the derailing member extending transversely of the rail and flexibly connected to the jaw for angular movement with respect thereto under car wheel impact.

9. In a portable derail, a derail block member, adapted to be placed against one side of the rail with its central transverse plane substantially covering the vertical face of a tie, a clamping jaw adapted to engage the opposite side of the rail adjacent said face of the tie, a road-bed abutment adapted to engage the top surface of the tie and a clamp-screw operatively associated with said clamping jaw, said screw and abutment being located close together on opposite sides of the central transverse plane of the block member.

10. A portable derail having a derail block member, and a leveling screw and a clamp-screw mounted side by side in the derail block member on opposite sides of the central transverse plane of the derail.

11. A portable derail having a derail block member, an adjustable road-bed-abutment adjacent the central transverse plane of the derail and between the same and the heel of the derail, a clamping jaw constituting the complementary clamp member for the derail block member, and a clamp-screw operatively connected to said clamping jaw and located adjacent the central transverse plane of the derail between it and the toe of the derail.

12. A portable derail comprising a derail block member seating on the rail tread and a jaw member adapted to clamp the rail between them, the derail having a supporting bearing upon the roadbed at the side of the rail, and clamp operating means, the point of initial wheel flange contact with the trough of the derail being at or beyond the line joining the supporting bearing with the toe of the derail, said supporting bearing

and clamp operating means being close together on opposite sides of a plane transverse of the derail.

13. A portable derail comprising a derail block member adapted for engagement with the top and side of the rail head, in combination with a supporting bearing at the side of the rail and means for clamping said member upon said bearing and rail, said clamping means comprising a clamp-screw rotatably mounted in the derail block member closely adjacent the supporting bearing and threaded into the clamping jaw with respect to which it is relatively turnable endwise of the rail under car wheel impact.

14. A portable derail comprising a derail block adapted to seat on the rail tread and on one side of the rail head and constituting a clamping member, a jaw adapted to bear on a part of the rail and constituting a complementary clamping member, an adjustable road bed bearing mounted in the derail block member, and power means for operating the clamping jaw connected thereto by means permitting relative movement endwise of the rail under car wheel impact, said road bed bearing and power means being close together, the point of initial contact of the wheel flange with the trough of the derail being at or beyond the line joining the road-bed bearing and the toe of the derail.

15. A portable derail having a derail block member adapted to seat on the tread of the rail and on one side of the rail-head, a clamping-jaw having a rail clamping contact surface, a clamp-screw having bearings in the derail block member and located in substantially the same plane with the rail clamping bearing surface of the clamping jaw, said plane being inclined to the web of the rail, and connections between said clamp-screw and jaw permitting relative turning movement in said plane under car wheel impact to materially increase the clamping action.

16. A portable derail comprising a clamp member consisting of a derail block member adapted for engagement with the top and side of the rail head, and a complementary clamp member adapted for engagement with the opposite side of the rail, in combination with a clamp-screw revolvably seated in the derail block member and capable of relative pivotal movement in vertical and lateral directions with respect thereto and having threaded engagement with the complementary clamp member, the connections between the clamp-screw and said complementary clamp member permitting relative movement endwise of the rail under car wheel impact.

17. A portable derail comprising a derail block member having a bearing surface for the rail tread and a shoulder for engagement with the side of the rail, in combination with means for clamping said member in a direc-

tion inclined to the web of the rail upon the rail, said means having a universal bearing in the derail block member and comprising members connected to each other by screw-threading and by bearing surfaces permitting relative turning movement in the direction of the length of the rail under car wheel impact.

18. A portable derail comprising a clamping member consisting of a derail block member and adapted to seat on the tread and on one side of the rail head, a jaw adapted to be hooked over the opposite edge of the rail base and constituting the complementary clamping member, a clamp-screw mounted in universal bearings in the derail block member and threaded in said clamping jaw, and means for permitting relative turning movement endwise of the rail between said clamp-screw and jaw under car wheel impact.

19. A portable derail comprising derail block and jaw members, and a clamp-screw rotatably mounted in the derail block member and engaged with the jaw member, the jaw member having a convex bearing surface to afford rocking contact with the rail and having its end remote from said convex surface permanently out of binding contact with the derailing member and free to move relatively to the derailing member and to the clamp-screw endwise of the rail under car wheel impact.

20. A portable derail comprising a clamp member consisting of a derail block member adapted to seat on the tread and on one side of the rail head, a complementary clamping jaw having a terminal hook for engagement with the rail base at the other side of the rail and having in line therewith a bore widened laterally, i. e. lengthwise of the rail, and having a recess adjoining said bore, in combination with a clamp-screw in said bore rotatably mounted in bearings in said derail block member permitting limited lateral movement, and a clamp-screw nut held against rotation in said recess, and bearing surface for said nut adjacent said bore and recess, the construction permitting the axes of said bolt and bore to move out of line in the direction of the length of the rail under wheel impact.

21. A portable derail comprising a clamp member consisting of a derail block member adapted to seat on the rail head, complementary clamping means and operating means aligned therewith mounted in the derail block member, said aligned operating and clamping means having capability of moving out of alignment on endwise movement of the derail block member.

22. In a portable derail a clamping jaw provided with a terminal hook and having opposed thereto a housing for a clamp-screw and for its non-rotatable nut, and a bearing for said nut in the housing.

23. In a portable derail a clamping jaw having a bore adapted to receive a clamp-screw and widened laterally toward its outer end and having adjacent the other end of said bore a bearing surface surrounding the same, and a recess adjacent said bearing surface adapted to receive a clamp-screw nut adapted to said bearing surface.
24. In a portable derail a clamping jaw having a terminal hook and in line therewith a bore widened in the plane of the bore and hook toward the end of the bore remote from the hook and having a recess adjacent the narrow end of the bore closed on one side in said plane.
25. In a portable derail a clamping jaw having a clamp-screw-receiving bore and adjacent the same a clamp-screw-nut-receiving recess provided with means for preventing rotation and travel of the nut, the bore being widened laterally from the end adjacent the recess for the nut to its other end.
26. A portable derail having a derail block member adapted to seat on the rail, a complementary clamping member therefor, power means connecting said members to clamp the rail between them, said power means having capability of relative turning movement endwise of the rail with respect to one or both of said members under car wheel impact, and a road bed abutment carried by the derail, the point of initial contact of the car wheel flange with the trough of the derail being at or beyond the line joining said roadbed abutment and the toe of the derail.
27. A portable derail having a derail block member adapted to seat on the rail head, a clamp member engaging the rail below the rail head, power means operatively connected to said derail block member and clamp member to clamp the rail between them, said structure being adapted to permit relative turning movement between the derail block member and the clamp member, under car wheel impact, sufficient to materially increase the clamping action.
28. A portable derail comprising rail clamping members, one of which is the derail block member adapted to seat on the rail, and power means operatively connected to said members for clamping the rail between them, said structure including line connections extending crosswise of the rail and flexible lengthwise of the rail under car wheel impact to reduce transverse strain on the connections and materially increase the clamping action.
29. A portable derail having a derail block member adapted to seat on the head of the rail, and a clamp member adapted to clamp the rail between them, said clamp member having a rail base engaging end and a free end on the other side of the rail disengaged from the rail, adapted to swing about the bearing on its rail engaging end on the rail base, under car wheel impact, and spaced from the derail block member sufficiently to prevent obstruction of such swinging movement by any part thereof.
30. A portable derail having a derail block member adapted to seat on the rail head, a clamp member engaging the rail below the rail head, a clamp screw mounted for rotation in the derail block member and having screw-threaded connection with the clamp member to clamp the rail between them, said structure being adapted to permit relative turning movement between the derail block member and the clamp member, under car wheel impact, sufficient to materially increase the clamping action.

In testimony whereof, I have signed this specification.

STANLEY W. HAYES.
